WALL SHELF

Marvin L. Cantrell, Pueblo, Colo.

Application August 20, 1953, Serial No. 26,521

Term of patent 7 years

(Cl. D33—3)

To all whom it may concern:

Be it known that I, Marvin L. Cantrell, a citizen of the United States, residing at Pueblo, in the State of Colorado, have invented a new, original, and ornamental Design for a Wall Shelf, of which the following is a specification, reference being had to the accompanying drawing, forming part thereof:

I claim:

The ornamental design for a wall shelf, as shown.

MARVIN L. CANTRELL.
